SURGICAL TABLE

Herbert P. Welland, Verona, Wis.

Application January 23, 1953, Serial No. 332,863

4 Claims. (Cl. 311—9)

1

This invention relates to improvements in tables and more particularly to auxiliary surgical tables suitable for preparatory and operative use.

Ordinary operating tables which have been used for the past forty years both in hospitals and in physicians' offices are designed for a maximum number of types of operations. While these designs are now the result of years of constant experimentation and improvement, they are still subject to certain limitations due to the fact their permanency reduces their flexibility. These tables are heavy and in many instances made a fixture of the room in which they are located, making adjustments to certain relatively simple proceedings extremely difficult.

It is therefore the principal object of the present invention to provide a new and simple auxiliary surgical table well adapted to meet varying conditions of use encountered in the ordinarily restricted confines of surgical operating rooms.

A more particular object is to provide a table of the above character particularly useful in hospitals and physicians' offices in pre-operative scrubbing and preparing lacerations and compound fractures of the head, scalp, arms, legs, hands and feet.

Another object is to provide a table of the above character the use of which will be simple and which may be quickly and easily operated by the physician or other attendant.

Another object is to provide a table of the above character which is portable and may be used as an independent unit.

Another object is to provide a table of the above character which is readily adjustable to the height desired.

Another object is to provide a table of the above character which will be neat and attractive in appearance and yet be of such sturdy construction as to withstand hard usage.

Another object is to provide a table of the above character which may be manufactured simple and practically from inexpensive material.

Other objects and advantages of the invention will be in part obvious and in part pointed out hereinafter in connection with the following detailed description taken in conjunction with the accompanying drawings wherein a preferred embodiment of the principles of the invention has been selected for exemplification.

In the drawings:

Fig. 1 is a perspective view of the table in use;

Fig. 2 is a cross sectional view taken along the line 2—2 of Fig. 1; and

Fig. 3 is a partial cross sectional view slightly enlarged taken along the line 3—3 of Fig. 1.

2

Referring now to the drawing wherein similar reference characters refer to similar parts throughout the several views, an auxiliary surgical table of the character of the present invention is indicated generally by the reference numeral 10 shown in an operative position at the head of a surgical operating table or bed 11 upon which a patient 12 is lying. Essentially the table 10 comprises an adjustable stand 13 which supports a removable pan 14 and a cooperating screen cover 15 for the pan.

The stand 13 comprises two vertical telescoping supporting members 16 and 17 secured, as by welding or any other suitable means, at their lower ends to two horizontally positioned feet 18 and 19. Between feet 18 and 19, and rigidly secured thereto, is a spacing bar 20 preferably made of light tubular metal. Telescoping members 16 and 17, whose upper portions are slidably mounted within their lower portions, are adjustably fixed in any selective position by set screws 21. Centrally positioned on a horizontal plane and welded to the upper ends of telescoping members 16 and 17 is a rectangular metal ring 22, shown in cross section only in Figs. 2 and 3. Ring 22 is constructed of cylindrical stock of a diameter approximately the size of the upper portions of telescoping members 16 and 17. To facilitate the raising and lowering of telescoping members 16 and 17 after the set screws 21 have been loosened are tabs 23 and 24, respectively, which are welded to the ring 22 at a point directly above the upper ends of these members, as best shown in Fig. 3. Tabs 23 and 24 are preferably of sufficient rigidity and extend so that, in addition to their function of raising and lowering the table, they may also serve as handles to carry or move the table from one location to another.

Rectangular pan 14 which may be constructed of porcelain or chromium plated metal or stainless steel, rests within ring 22 on its horizontal peripheral flange 25. Flange 25 extends only to the outside measurements of ring 22 and is not secured thereto so that pan 14 may be removed at will. When desired a series of interchangeable pans 14 and screen covers 15 may be provided and alternately used so that sterilization thereof need not interrupt continuous use of the table.

Cover 15 comprises a metal frame 26 having an overhanging lip 27 which fits snugly over flange 25 of pan 14 and a body portion of metal wire mesh 28, of approximately $\frac{1}{2}$ inch size, whose edges are welded to the underside of the frame 26. The lip 27 of the frame 26 is notched at either end as at 29 to accommodate tabs 23 and 24 which

extend beyond the frame thereby to position and tend to secure the cover upon the pan.

The operation of the table is quite simple. By means of the set screws 21 it may easily be adjusted to any desired height. The pan 14 is removable as is the cover 15 which greatly simplifies cleaning and sterilization. The open mesh cover permits full support while the pan readily acts as a receptacle for waste liquid and blood.

The stand and pan may be used independently of the cover in certain instances, such as a receptacle for used sponges, bandages, or other refuse of an operation. When the cover is placed over the pan, the wire mesh offers firm support of a limb permitting free drainage through and into the pan below, which is most desirable in some types of operation.

The adjustability of the stand greatly increases its usefulness. It is not only suitable for use with standard operating tables which are appreciably higher than ordinary beds but it may be lowered to the level of a cot or bench such as might be found in a physician's office.

Inasmuch as the present invention embraces many embodiments and the embodiment above set forth is capable of many changes, it is to be understood that all matter hereinabove set forth, or shown in the accompanying drawing, is to be interpreted as illustrative and not in a limiting sense.

I claim:

1. An auxiliary surgical table comprising, a stand having vertically adjustable telescoping supporting members, a horizontally positioned ring secured to said supporting members, a pan supported by said stand within said ring, and a wire mesh cover for said pan, said pan and cover providing a supplementary operative area and a cooperating receptacle for refuse.

2. An auxiliary surgical table comprising, a stand having vertically adjustable telescoping supporting members, means to lock said support-

ing members in a selective position, a ring secured in a horizontal plane to said supporting members, a removable pan supported by said stand within said ring, and a wire mesh cover for said pan, said pan and cover providing a supplementary operative area and a cooperating receptacle for refuse.

3. An auxiliary surgical table comprising, a stand having vertically adjustable telescoping supporting members, tabs secured to the upper ends of said supporting members projecting outwardly and at right angles from said members to raise and lower said members, means to lock said supporting members in a selective position, a ring secured in a horizontal plane to said supporting members, a removable pan supported by said stand within said ring, and a wire mesh cover for said pan, said pan and cover providing a supplementary operative area and a cooperating receptacle for refuse.

4. An auxiliary surgical table comprising, a stand having vertically adjustable telescoping supporting members, tabs secured to the upper ends of said supporting members projecting outwardly and at right angles from said members to raise and lower said members, set screw to lock said telescoping supporting members in a selective position, a ring secured to the upper ends of said supporting members in a horizontal plane, a removable pan supported by said stand within said ring, and a removable wire mesh cover having a dependent lip fitting over said pan, said pan and said cover providing a supplementary operative area and a cooperating receptacle.

HERBERT P. WEILAND.
